UNITED STATES PATENT OFFICE

EDWARD O. NORRIS, OF GREENWICH, CONNECTICUT

SURFACING MACHINE

Application filed December 22, 1928. Serial No. 327,801.

This invention relates to surfacing machines for wood material and the like. My invention consists in the peculiar and novel construction of a surfacing machine adapted to level, dress, finish and polish wood or the like, said machine having means for revolving the dressing roller, means for reciprocating the dressing roller in a lengthwise direction.

- 10 A further object of this invention is to provide a surfacing machine having a cylindrical cylinder, so attached, as to make it easily removable for refilling with abrasive or polishing material.
- 15 A further object of this invention is to provide a surfacing machine, operated by flexible shafting, compactly arranged and easily carried about.

With these and other objects in view, the invention consists in certain novel features of construction as hereinafter shown and described, and then specifically pointed out in the claims, and in the drawings illustrative of the preferred embodiment of the invention.

- 25 In the accompanying drawings:
- Figure 1 is a plain view of the device.
- Figure 2 is a side view of the device.
- Figure 3 is a view taken on 3—3 Figure 1.
- Figure 4 is a detail of the surfacing ma-

30 terial.

Figure 5 is a side view of the device with a box and handle.

In the drawings, numerals refer to similar parts of the drawings.

- 35 The improved device, comprises a supporting frame 10, which includes spaced longitudinal rods 11 and 12, connected by a rod 13. Upon the rods 11 and 12, a flat member 14 is adapted to slide longitudinally.

- 40 The flat member 14, is stamped out of metal, and comprises end portions 15 and 16.

- The flat member 14 is provided with a projection 19. At the end of the projection, a link 20 is revolvably connected to the projection by means of a pin 21. At the other end of the link 20 another pin 22 is set, its function to be described later.

- The motive power for the device is obtained through a flexible shaft 23, within a tube 24.

- 50 On a plate 25, two collars 26 and 27 are

fastened. Between these collars there is set a worm gear 28. This worm gear is fastened to the shaft 29 which is the continuation of the flexible shaft 23 and rests in the collars as bearings.

The method of fastening the worm gear 28 to the shaft 29, is merely by flattening the shaft 29 at 30 and providing an opening in the worm gear with a similar flat side so as to prevent rotation on the shaft 29.

The shaft 29 extends and passes a downward projection 31 depending from the member 14.

A collar 32 is fitted on the shaft 33. A spur gear 34 is welded or otherwise attached to the collar 32.

Both collar 32, the spur gear 34 are adapted to move up and down the shaft 29.

The shaft extends until the point 35, where it is rounded and the point 35 rests within a tubular lug 36 on the rod 13.

On the plate 25, there is provided a double gear 37 revolving on a pin 38. The double gear consists of a large pinion 39, and small pinion 40. The large pinion is in mesh with the worm gear 28.

A block 41, is provided to which a small pinion 42 is rotatively connected by means of a pin 43.

A chain 44 travels on the two pinions 40 and 42.

The pin 22, mentioned heretofore, is connected to one of the links in the chain 44, and is made to follow the course made by the chain 44, and due to the link 20, which rotates on the pin 21, the turns around the pinions are easily made.

To the block 41 there is attached by welding or otherwise, a vertical bar 45. This bar is attached to the frame rod 11 and is held to by means of a nut 46.

The end portions 15 and 16 of the flat member 14, are adapted to support a surfacing element 47.

The end portion 15, is attached to a block 48, by means of screws 49 and 50. The lower portion of the block is bored at 51 so as to slide on the frame rod 11. The block is also provided with a recess 52, for supporting the axis 53, of the surfacing element 47. A

number of washers 54 are placed on the axis 53 for taking up space.

The other end portion 16 is also provided with a block 55 attached to the end portion by means of screws 56 and 57. The block 55 is also provided with opening 58 for sliding on the frame rod 12.

5 Into the block 55, there is also screwed a guide bar 59. This bar 59 passes through an opening 60 in the bar 45.

10 The frame member 12 extends through the block 41, and is held thereto by means of the shoulder 61 of the bar 12 and the nut 62 at the end of the bar 12.

15 The end portion 16 is provided with an extension 63 and a downwardly bent member 64. This member 64 is provided with an aperture 65 in which the axis 66 of the surfacing element is supported.

20 A bevel gear 67 is attached to the surfacing element and is in mesh with the spur gear 34.

25 The surfacing element 47 is made of a cylindrical form and to the surface of the cylinder there is attached the abrasive or polishing material as desired. The abrasive or polishing cloth is attached to the surfacing element so that the meeting edges of the material lie in a diagonal line 68, across the surfacing element.

30 In Figure 4, there is illustrated a roll of abrasive or polishing material 72. The numerals 69 and 70 refer to the dotted lines along which the material 72 is to be cut into portions to be attached to the surfacing element as shown. The circles 71 indicate pats of cement or glue for attaching the material to the element 47. Any other method of attaching can be used if desired.

35 In Figure 5, the device is shown with the operating means inclosed in a box 73, which is carried by a handle 74, and attached to said box by means of connections 75 and 76.

40 What I claim is:

45 In a surfacing machine, a surfacing element having a gear on one side of same, a shaft, a supporting member for said element, a spur gear connected to said shaft and meshing with said gear on the element, a worm gear on the shaft, a large pinion meshing with said worm gear, a small pinion attached to said large pinion, a second pinion set off from the small pinion, a link chain traveling on the last two mentioned pinions, a link 50 revolvably attached to said supporting member, a pin in the free end of said link, said pin being set in one of the links of said chain and adapted to travel with said chain for causing forward or backward movement of 55 said element.

60 Signed at Greenwich, Connecticut, in the county of Fairfield and State of Connecticut, this 12th day of November, A. D. 1928.

EDWARD O. NORRIS.
